GRAIN STORAGE BIN

Archie L. Carbaugh, Aitch, Pa.

Application January 28, 1943, Serial No. 473,848

1 Claim. (Cl. 214—16)

This invention relates to new and useful improvements in grain storage bins, the principal object of the invention being to provide a bin wherein grain can be conveniently removed from the bottom of the bin to the top for the purpose of contacting the grain with air and facilitating the drying thereof.

Another important object of the invention is to provide a grain storage bin in which grain can be conveniently moved from one point to another, thus subjecting the grain to air contact to dissipate any moisture inherency that may prevail.

Other objects and advantages of the invention will become apparent to the reader of the following description.

In the drawings:

Figure 1 represents a side elevational view of the improved bin.

Figure 2 is a fragmentary vertical sectional view through the bin.

Figure 3 is a horizontal sectional view taken substantially on the line 3—3 of Figure 1.

Figure 4 is a fragmentary vertical sectional view through the upper portion of the bin.

Figure 5 is a fragmentary outside elevational view of the gate controls.

Figure 6 is a fragmentary vertical sectional view taken substantially on the line 6—6 of Figure 3.

Figure 7 is a fragmentary detailed sectional view taken substantially on the line 7—7 of Figure 2.

Referring to the drawings wherein like numerals designate like parts, it can be seen that numeral 5 denotes a cylindrical side wall built up in sections and having a roof 6 at its upper end. The side wall structure is suitably mounted and anchored upon a concrete base 7.

The interior of the bin is divided by radially disposed partitions 8 into separate compartments A, B, C and D, for the storage of grain and this number may be increased or decreased depending upon the number of partitions 8.

These partitions 8 extend downwardly to the inclined floors 9, one for each bin compartment and each of these floors has a discharge opening 10 therein which is normally closed by a slide door 11, this door being operated by a screw shaft 12 operating on a nut 13 carried by the

door 11. This screw is swivelly supported by a bearing 14 and is operated by a crank handle 15.

Under each floor 9 is a sub-floor or chute 16 which catches grain falling through the overlying opening 10 and delivers the same to a trough 17 centrally located within the bin and adjacent the lower end thereof.

Numeral 18 denotes a stack which rises from the trough 17 and has inner edges of the partitions 8 connected thereto as suggested in Figure 3. This stack 18 rises to the roof 6 and opens into a small shed 19 located on the roof 6.

In this shed 19 is an electric motor 20 or other power plant for driving a shaft 21, carrying sprocket wheels 22 over which sprocket chains 23, 23 are disposed.

These sprocket chains depend in the stack 18 and pass under sprocket wheels 24 located on an idler shaft 25.

At predetermined intervals, the chains 23 are bridged as at 26 and these bridge members carry buckets 27.

The buckets travel downwardly, following the chains 23, filled with grain from the trough 17 and then pass upwardly, contacting the air draft in the stack 18, and then being dumped as the buckets pass over the upper sprocket wheels 22, where the grain passes through air and becomes substantially dehydrated.

Numeral 29 denotes a hopper for catching grain dumped from the buckets at the upper end of the stack 18 and the bottom of this hopper 29 has openings A', B', C' and D', conduits 30 extending from these openings to corresponding compartments A, B, and C as suggested in Figure 3, while the opening D' communicates the hopper 29 directly with the underlying compartment D. A fifth opening E in the bottom of the hopper 29 communicates with a chute 31 which leads to outside of the bin wall 5 as suggested in Figure 1.

A gate 32 is provided for each of the openings A', B', C', D' and E, and members 33 connect these gates, last mentioned, with bell cranks 34 mounted on the outside of the wall 5. Pull members 35 depend from the bell cranks 34 and terminate in knobs 36 located adjacent the hand cranks 15.

It can be seen, that by pulling the pull mem-

bers 35, grain can be delivered from the hopper 29 to any one of the compartments A, B, C and D.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

An apparatus of the character described comprising a storage bin provided with a vertical stack at the central portion thereof, partitions

in the bin dividing the interior of the bin into a plurality of compartments, an elevator in the stack for elevating grain from the bottom portion of the stack to the upper portion thereof, distributing means at the upper portion of the bin for distributing elevated grains to the various compartments, a loading chute beneath each compartment extending radially from the stack through the outer wall of the bin and adapted to feed the grain to the bottom of the stack, and valve means in the bottom of each compartment for admitting grain to the respective chutes.

ARCHIE L. CARBAUGH.
